[57] **CLAIM**

The ornamental design for a splash dampening cup, as shown and described.

DESCRIPTION

FIG. 1 is a top perspective view of a splash dampening cup showing my new design.

FIG. 2 is a top plan view thereof.

FIG. 3 is a bottom plan view thereof.

FIG. 4 is a right side elevational view thereof, wherein the left side elevational view is a mirror image thereof.

FIG. 5 is a sectional view thereof, taken substantially along lines 5—5 in FIG. 2.

FIG. 6 is a front elevational view thereof.

FIG. 7 is a rear elevational view thereof.
